Patented Sept. 20, 1927.

UNITED STATES PATENT OFFICE.

REINHOLD KUSSEROW, OF OAKLAND, CALIFORNIA.

PROCESS OF CLEANING MOLASSES FOR MANUFACTURING COMPRESSED YEAST.

No Drawing.

Application filed October 29, 1925. Serial No. 65,679.

This invention relates to processes of cleaning and sterilizing solutions used in manufacturing yeast of the compressed variety. In the past, compressed yeast has been largely manufactured by the propagation of yeast culture in grain mashes. However, in my copending application, Ser. No. 711,833, filed May 8, 1924, I have described a process of manufacturing yeast from molasses by which process a high quality of yeast may be cheaply obtained. The process herein described is an improvement over the process described in the above application.

In manufacturing yeast from molasses or other substances containing a high percentage of sucrose, especially the crude sugar cane molasses, it is difficult to properly sterilize and clean the molasses solution in order to kill certain injurious germs and bacteria originally present in the crude molasses. Some of these germs, especially those of butyric acid bacteria, cannot be destroyed by the use of the usual mineral acids or by simply heating to high temperatures. Furthermore, the use of mineral acids is objectionable in that in many kinds of molasses and especially in cane sugar molasses, it causes the formation of certain colloids. These colloids cannot be readily separated from the solution and a yeast propagated in such a liquid produces a slimy product which contains certain of the germs found in the original molasses. Such a yeast product spoils very rapidly and cannot readily be compressed in filter presses.

To make it possible to employ common commercial molasses and even the crude sugar cane molasses in the manufacture of yeast, I have evolved a new process of cleaning and sterilizing a solution of molasses prior to the seeding or pitching of the solution with yeast. By this process the solution is sufficiently clarified and is freed from injurious germs and bacteria. Yeast manufactured from such a solution is practically free from slimy colloids, may be readily compressed, and will not easily spoil.

This process was made possible thru the discovery that dilute molasses solution after the addition of sufficient alkali to prevent the propagation of wild yeast, can be employed for the propagation of lactic acid and other kinds of bacteria. The process developed utilizes the development of certain bacteria present in the molasses solution, especially lactic acid bacteria, which bacteria propa-

gate between approximately from 20 to 30° C. in an alkaline solution. Other acid forming bacteria which are initially present in crude molasses and which will also propagate under such conditions are butyric acid bacteria mentioned above, and bacterium megateroides mentioned in Delbrück, Brennerei Lexicon, Berlin, Germany, 1915, page 519. The propagation of these bacteria in this manner effects a decomposition of the undesired colloids. Subsequently after complete propagation they may be readily killed by the application of heat and the solution used to propagate lactic acid bacteria growing at a relatively high temperature. However, this latter part of the process is only necessary in case very impure molasses is used.

In practice the process is carried out as follows: The crude molasses, or other material containing a relatively high percentage of sucrose, is diluted with water to about twenty five degrees "balling". The solution is then made alkaline preferably by the addition of from one fourth to one percent by weight of calcium hydrate to prevent the propagation of wild yeast. After thoroughly dissolving and mixing the calcium hydrate, the solution is allowed to stand at a temperature ranging from 20 to 30° C. for 6 to 24 hours or longer. The cleaning process may be further improved by the addition of an oxidizing substance to the solution, such as potassium permanganate, potassium chlorate, or some peroxide. About 0.01 to 0.1% by weight is usually sufficient. During this time bacteria previously mentioned as being initially in the crude molasses is allowed to propagate to form certain complex organic acids. Propagation of the bacterium megateroides serves to decompose nitric acid which is present in many kinds of crude molasses and which is detrimental to yeast propagation. Propagation of bacteria under such conditions results in the decomposition of the undesired colloids to form a dark insoluble precipitate and certain soluble compounds which are valuable yeast nutriments. The precipitate readily settles out of the solution.

In case highly infected molasses is employed for manufacturing yeast, after completing the above step, the solution may be slowly heated up to the relatively higher temperature of about 60° C. and lactic acid bacteria which propagate at temperatures

from 50 to 60° C. are added. Lactic acid bacteria which will propagate at this temperature have been well known and are described in a publication entitled "Mitteilungen für Brennerei und Preszhefefabrikation", printed Oct. 18, 1905, by Hemann Brandt, Custrin, Germany, of which I am the author. The bacteria mentioned in this article, page 2, grow at about 59° C., the well-known bacterium delbrücke growing at about 50° to 55° C. may also be used. In heating the solution up to this temperature, the germs and bacteria in addition to the lactic acid bacteria which have previously been allowed to propagate between 20 to 30° C. are readily killed by a comparatively low temperature and thus the solution is sufficiently sterilized. Sterilization carried on under these conditions will kill detrimental bacteria and germs which otherwise could not be killed either by mineral acids or high temperatures. The organic acids which have been produced by the bacteria propagating between 20 to 30° C. are useful in that they form a food for the yeast which is subsequently propagated.

Following the introduction of the lactic acid bacteria, the solution is allowed to stand from 12 to 48 hours at a temperature ranging approximately from 50 to 60° C. During this time the decomposition of the colloids is completed and the precipitate may be separated out to leave a clear liquid. It is preferable to separate out the precipitate several times during the process. Also during the entire process the solution should be kept alkaline until completion of the propagation of the lactic acid bacteria if necessary by adding additional calcium hydrate.

The solution is now in condition to be employed for the propagation of yeast. The detrimental germs and bacteria propagating between 20 to 30° C. have been killed by heating to 60° C. However, to insure complete sterilization, the solution may be heated to from 70 to 80° C. The lactic acid bacteria which were added are not injurious to the growth of the yeast and need not be killed.

It should be understood that other materials may be employed during the above process to produce an alkaline solution. For example, I may use any other soluble substances of alkaline reaction such as barium hydrate, sodium hydrate, potassium hydrate, ammonia, alkaline carbonates, silicates or basic phosphates. It is sufficient if the quantity present prevents the propagation of wild yeast but allows the development of acid forming bacteria.

During or after development of the lactic acid bacteria in the molasses it is profitable to add about 0.1% by weight of a reducing substance, preferably sodium thiosulphate, the use of which is described in my copend-

ing application No. 711,833, previously mentioned. This should be added subsequent to the addition of any oxidizing substance.

When certain kinds of molasses are employed, it is possible to sufficiently disintegrate the colloids and to eliminate certain detrimental bacteria by merely promoting the propagation of bacteria at the higher temperatures of from approximately 50° to 60° C. in a dilute alkaline solution of the molasses, thus eliminating the step of promoting the growth of bacteria propagating at from 20 to 30° C.

The solution resulting from this process is lacking in certain yeast foods and accordingly it is necessary to add phosphates and ammonia salts or organic solutions made from grain. The resulting solution is then diluted with water and pitched or seeded with yeast in any well known manner and the process of yeast propagation completed.

Yeast which is manufactured from a solution prepared by this process will be of highest quality and texture and will be free from slimy substances. It may be readily compressed with or without the addition of starch and will not readily spoil.

I claim:

1. The process of preparing crude molasses for the manufacture of yeast comprising decomposing colloids in said molasses to form a precipitate by promoting the propagation of lactic acid bacteria in an alkaline solution of said molasses.

2. The process of preparing crude molasses for the manufacture of yeast comprising promoting the propagation of lactic acid bacteria in a dilute solution of the molasses maintained at a temperature of from 20 to 30° C., the solution being maintained alkaline to prevent the propagation of wild yeast.

3. The process of preparing molasses for the manufacture of yeast comprising adding living lactic acid bacteria to a dilute solution of the molasses, the bacteria being such as will propagate at a temperature substantially from 50 to 60° C., and maintaining the solution at a temperature of from 50 to 60° C. for a substantial period, to complete the decomposition of the colloids and to form soluble yeast nutriments and a precipitate readily separable from the solution, the solution being maintained alkaline throughout the process.

4. The process of preparing crude molasses for the manufacture of yeast, the molasses initially containing lactic acid bacteria which will propagate at a temperature of from 20 to 30° C., the process comprising promoting the propagation of lactic acid bacteria in a dilute solution of the molasses maintained at said temperature for a substantial period, killing said bacteria by the application of a higher temperature, adding

- living lactic acid bacteria of a variety which will propagate at a temperature of from 50 to 60° C., and promoting the propagation of said latter bacteria in said solution at said last named temperature, the solution being maintained alkaline throughout the process.
5. The process of preparing crude molasses for the manufacture of yeast comprising promoting the propagation of lactic acid forming bacteria in a dilute alkaline solution of the molasses to which is added an oxydizing substance.
6. The process of preparing molasses for the manufacture of yeast comprising promoting the propagation of lactic acid bacteria in a dilute alkaline solution of the molasses and adding a reducing substance to said solution.
7. The process of preparing molasses for the manufacture of yeast comprising promoting the propagation of lactic acid bacteria in a dilute alkaline solution of the molasses and adding sodium thiosulphate to said solution.
8. The process of preparing crude molasses for the manufacture of yeast comprising promoting the propagation of lactic acid forming bacteria in a dilute alkaline solution of the molasses and adding an oxydizing substance and a reducing substance subsequent to the addition of the oxydizing substance.
9. The process of preparing crude molasses for the manufacture of yeast, the molasses initially containing lactic acid forming bacteria which will propagate at a temperature of from 20 to 30° C., the process comprising promoting the propagation of said bacteria in a dilute alkaline solution of said molasses.
10. The process of preparing crude molasses for the manufacture of yeast, the molasses initially containing lactic acid bacteria which will propagate at a temperature of from 20 to 30° C., the process comprising promoting the propagation of said bacteria in a dilute solution of said molasses at a temperature from 20 to 30° C., the solution being maintained alkaline to prevent the propagation of wild yeast.

In testimony whereof, I have hereunto set my hand.

REINHOLD KUSSEROW.
